UNITED STATES PATENT OFFICE

GEORGE L. TULLY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS

OPHTHALMIC MOUNTING

Application filed March 21, 1931. Serial No. 524,303.

This invention relates to improvements in connecting or securing means and has particular reference to improved means for uniting the parts of an ophthalmic mounting.

The principal object of the invention is to provide an improved connection or securing device for uniting the parts of an ophthalmic mounting wherein the said parts may be quickly interchanged or adjusted.

Another object of the invention is to provide improved means for connecting the lens holding members of an ophthalmic mounting wherein the distance between said members may be quickly and easily adjusted to fit the facial requirements of the wearer.

Another object is to provide an improved adjustable bridge for an ophthalmic mounting and improved means of attaching the said bridge to the lens holding members of said mounting.

Another object is to provide improved means for securing the attaching means against displacement and consequently preventing the connecting means from becoming loose or detached from the lens holding members during the use of the ophthalmic mounting.

Another object is to provide a connecting or securing device which is simple and efficient in its nature and operation and which may be quickly and economically manufactured.

Other objects and advantages of the invention will be apparent from the following description taken in connection with the accompanying drawings and it will be understood that many changes may be made in the details of construction and arrangement of parts without departing from the spirit of the invention as expressed in the accompanying claims. I therefore do not wish to be limited to the exact details shown and described as the preferred forms only have been shown by way of illustration.

Referring to the drawings:

Fig. I is a front elevation of an ophthalmic mounting embodying the invention showing a portion thereof in section;

Fig. II is a perspective view of one of the

lens holding members showing a portion of the lens retaining means broken away to expose the edge of the lens;

Fig. III is an enlarged fragmentary sectional view taken on line III—III of Fig. II;

Fig. IV is a sectional view taken on line IV—IV of Fig. I showing the parts disunited;

Fig. V is a view similar to Fig. III, showing a modified form of the invention;

Fig. VI is a fragmentary view of the interior of the lens holding member shown in Fig. V showing a face view of the connecting means;

Fig. VII is a fragmentary perspective view of another modified form of the invention;

Fig. VIII is a perspective view of the connecting means shown in Fig. VII; and

Fig. IX is a fragmentary sectional view of a further modification of the invention.

With certain types of ophthalmic mountings particularly eye protectors and goggles it is necessary that the mounting be so formed that the distance between the lens holding members may be adjusted to fit the facial requirements of different individuals. In prior art mountings where attempts have been made to accomplish this result it has been found difficult to produce a connection that will hold the bridge member securely in position and yet be so constructed that the distance between the lens holding members may be easily and quickly adjusted.

It is therefore the prime object of my invention to provide a simple and efficient connection of the bridge means to the lens holding members of an ophthalmic mounting wherein the said bridging means may be easily and quickly adjusted to the requirements of the wearer and be held securely in the adjusted position during the use of the mounting.

Referring more particularly to the drawings in which similar characters of reference designate corresponding parts throughout the several views the device to which the invention is shown applied comprises a pair of eyecup members 1 which are formed with a face contacting edge 2 shaped to the contour of the face and a threaded portion 3 to which

a threaded lens retaining ring 4 is attached to secure a protection lens 5 within the eyecup.

The eyecup members 1 are connected centrally by a bridge member 6 and are provided with a suitable head band 7 to hold the mounting on the face of the wearer.

A perforated shield member 8 is secured over an opening in the side of the eyecup 1 to provide the necessary ventilation.

The preceding construction is of a commonly known goggle or eye protector and may be varied at will as may seem necessary to obtain the best results as the improved connecting or securing device embodying the invention may be used with many different constructions.

The bridging member 6 shown in Figures I to VII inclusive is flexible and is formed of a plurality of ball members 9 connected in spaced relation by a series of link members 10. The bridge member is covered by a tubular member 11 which may be formed of a non inflammable substance, rubber or other soft protective material.

The connection of the bridge member 6 to the eyecups is formed by piercing the side walls of the eyecups to form an opening 12 therethrough in which the ends of the bridge member 6 are secured. The securing means as shown in Figures I to IV inclusive is formed of a plate member 13 pivoted at 14 to the interior of the eyecup. The plate member is provided with a slot 15 which straddles a link member 10 between the ball members 9 and in this manner securely attaches the end of the bridge member to the eyecup. When the plate member 13 is in locked position on the link member 10 as shown in Figures II and III and the lens 5 has been secured in the eyecup, the end 16 of the plate 13 opposite the pivot connection 14 engages the under surface of the lens 5 and is in this manner held against displacement. This prevents the possible loosening and detaching of the bridge member during the use of the mounting.

An up turned portion 17 formed on the end 16 provides a thumb piece by which the plate 13 can be easily moved on its pivot.

When it is desired to interchange or adjust the bridge member 6 the retaining ring 4 and lens 5 are removed from the eyecup and the plate member 13 is then moved outwardly on its pivot 14 as shown in Fig. IV. This permits the end of the bridge member to be adjusted or detached from the eyecup.

Both ends of the bridge member 6 can be removable from the eyecups if desired or one end can be permanently attached to one of said eyecups.

A slight modification of the invention is shown in Figures V and VI wherein the bridge member can be detached and adjusted without disturbing the lens 5. This is ac-

complished by pivotally mounting a plate member 18 so that it is free to rotate without engaging the lens 5. In this instance the plate member 18 is provided with a projection 19 which when the plate member is in locked position with the bridge 6 extends into a recess 20 in the eyecup and holds the plate member against displacement during the use of the mounting. The projection 19 is held in the recess 20 by the resiliency of the plate member 18. A lip 21 is formed on the plate member 18 adjacent the projection 19 so that the said projection can be lifted out of the recess 20 when it is desired to move the said plate member to interchange or adjust the length of the bridge.

Another modification is shown in Figures VII and VIII wherein a split washer member 22 is employed instead of the pivoted plate members 13 and 18. When the desired length of bridge is obtained the split washer 22 is forced over the link member 10 between the ball members 9 and thereby secures the end of the bridge member to the eyecup. The washer functions similarly to the plate members 13 and 18 but is not secured to the eyecup.

In Fig. IX there is shown a further modification wherein a chain bridge member 23 is used instead of the ball and link arrangement referred to above. In this instance the slot 15 in the plate member 13 straddles one of the link members 24 adjacent the end of the bridge and the normally related link member 25 at the end of the bridge engages with the side of the plate member and locks the said bridge in the eyecup.

The plate 13 may also be formed with a projecting lug member 26 adjacent the slot 15 which when the chain bridge member 23 is used can be extended within the link member 24 or 25 to lock the bridge member to the eyecup. With this type of plate member either the ball and link bridge 6 or chain bridge member 23 can be used and the said chain bridge can be attached to the eyecup through the use of the slot 15 or projecting lug 26 as desired.

From the foregoing it will be seen that I have provided simple, efficient and economical means of carrying out the objects of the invention, particularly in providing extremely simple and efficient means for allowing the bridge member to be easily and quickly adjusted and for locking it in adjusted position so that it cannot become disengaged while the mounting is in use.

Having described my invention, I claim:

1. In a device of the character described, an eyecup having an opening on its nasal side, a bridge member having an end extending through the opening in the eyecup and a pivoted lock member engaging the end of the bridge extending into the eyecup to hold the

bridge end against withdrawal from the opening.

2. In a device of the character described, an eyecup having an opening on its nasal side, a bridge member having an end extending through the opening in the eyecup, a pivoted lock member engaging the end of the bridge extending into the eyecup to hold the bridge end against withdrawal from the opening, and additional lock means to lock the pivoted lock against displacement from engagement with the bridge member.

3. A bridge connection for an ophthalmic mounting comprising a lens holding member having an opening therein, a bridge member having a portion adjacent its end extending into the opening and a slotted plate member engaging the end of the bridge member internally of the lens holding member to secure the said end against withdrawal from the opening.

4. A bridge connection for an ophthalmic mounting comprising an eyecup member having an opening therein, a bridge member having a portion adjacent its end extending into the opening and a plate member pivotally connected to the eyecup member internally thereof and having a slotted portion engaging the bridge member adjacent its end internally of the eyecup to secure the said end against withdrawal from the opening.

5. A bridge connection for an ophthalmic mounting comprising a lens holding member having an opening and a groove in the side wall thereof, a bridge member having a portion adjacent its end extending into the opening, a plate member pivotally connected to the lens holding member internally thereof and having a slotted portion engaging the bridge member adjacent its end internally of the lens holding member to secure the said end against withdrawal from the said opening and a projection on the plate member adjacent its end opposite the pivot connection

45 fitting into the groove in the lens holding member to hold the said plate member against movement when the slotted portion thereof is in engagement with the portion adjacent the end of the bridge member.

50 6. A bridge connection for an ophthalmic mounting comprising a lens holding member having an opening therein, a lens in the lens holding member, means for securing the lens in the lens holding member, a bridge member having a portion adjacent its end extending into the opening in the lens holding member and a plate member pivotally connected to the lens holding member internally thereof and having a slotted portion engaging the bridge member adjacent its end internally of the lens holding member to secure the said end against withdrawal from the opening in said lens holding member, said plate member having a portion thereof engaging the under surface of the lens and being held

against movement on its pivot by said lens when the parts are in assembled position.

7. In a device of the character described, a pair of lens holding members, one of which has an opening in its side wall, a flexible bridge member secured adjacent one of its ends to one of the lens holding members and having its opposite end portion extending into the opening in the other lens holding member and a slotted plate member secured adjacent the end of the bridge member internally of the lens holding member for securing the said end against withdrawal from the opening.

8. In a device of the type described, a pair of eyecups, a bridge member connecting said eyecups and having a series of enlargements thereon, a lock member on one of said eyecups having means to engage one of the enlargements on said bridge and secure the bridge to the eyecup, said lock member being movable into and out of engagement with said bridge member to allow the bridge member to be adjusted.

9. In a device of the type described, a pair of eyecups, a chain bridge member consisting of a series of links connecting said eyecups and a lock member on one of said eyecups having means to engage one of said links and secure said bridge to the eyecup, said lock member being movable into and out of engagement with said bridge member to allow said bridge member to be adjusted.

10. In a device of the type described, a pair of eyecups, a bridge member connecting said eyecups and having a series of enlargements thereon, a pivoted lock member on one of said eyecups having means to engage one of the enlargements on said bridge and secure the bridge to the eyecup, said pivoted lock member being movable into and out of engagement with said bridge member to allow the bridge member to be adjusted.
